UNITED STATES PATENT OFFICE

152,843

DESIGN FOR A COMBINATION MOP HEAD
AND HANDLE SOCKETFranz Wagner, Chicago, Ill., assignor to O-Cedar
Corp'n, Chicago, Ill., a corporation of Illinois

Application January 21, 1948, Serial No. 143,956

Term of patent 14 years

(Cl. D9—2)

To all whom it may concern:

Be it known that I, Franz Wagner, a citizen of the United States, residing at Chicago, county of Cook, and State of Illinois, have invented a new, original, and ornamental Design for a Combination Mop Head and Handle Socket, of which the following is a specification, reference being had to the accompanying drawing, forming a part thereof, in which:

Figure 1 is a top plan view of a combination mop head and handle socket, showing my new design; Fig. 2, a perspective view; Fig. 3, a rear view in elevation; Fig. 4, a side view in elevation; and Fig. 5, a front view in elevation.

I claim:

The ornamental design for a combination mop head and handle socket, as shown.

FRANZ WAGNER.
